ABSTRACT OF THE DISCLOSURE

A method of securing a plastic container and a metal bottom section therefor together by an interlocked joint is provided. A downwardly extending end wall of the container is received in an upwardly open groove in the bottom section and is secured therein by special localized rolling forces applied initially to the inner wall of the groove and thereafter to the outer wall of the groove. The upper surface of the bottom section may be reinforced while forcing the outer wall inwardly.

The present invention relates to containers, and especially to a combined metal and plastic article or container and to a method of attaching a metal base plate or section to a wall of a plastic container to form a water-tight article.

Heretofore there have been various efforts made to provide some type of a container, at least primarily made from a plastic material, which is adapted to have heat supplied thereto for heating the contents of the container. A percolator is one example of such type of a container and in this instance it is necessary to attach a metal base plate to the container to close an opening formed in the bottom portion of the container in order to obtain an operative structure. Containers of this type have been proposed heretofore for use as coffee percolators, for example, although any type of a cooking utensil, or water heating member is contemplated to be made by the method of the present invention.

Specifically, with plastic containers and metal bottoms, or base sections therefor, the different coefficients of expansion and contraction of the materials involved have made it difficult to secure them together by a water-tight joint. Also, some of such members as proposed heretofore have had the joint, or connection between the plastic and the metal formed on a generally vertically extending axis, at least substantially the same axis on which the separating forces between the plastic container and the bottom plate are applied whereby it is difficult to obtain a water-tight, permanent connection between a wall of the plastic article or container and the metal bottom plate or section.

These water-tight containers or articles are subjected to severe stresses in use. For example, the articles may be heated to relatively high temperatures with nothing in the plastic container and this produces appreciable thermal distortion of the metal bottom plate and/or the container and/or the connection therebetween. In ordinary use, the container is repeatedly put through heating and cooling cycles covering a range of about 100°, or more. All of such heating and cooling actions on the container naturally stress it and the components thereof severely and particularly stress the connection formed between the plastic and metal sections thereof.

The general object of the present invention is to provide a novel and improved method of obtaining a water-tight article from a plastic container section having an end wall defining a bottom opening therein and a metal

2

bottom or base plate for the plastic container section or portion.

Another object of the invention is to use the distortion, resiliency and shaping of a radially inner wall of a groove in a metal plate to aid in securing a container wall in the groove in the metal plate by distortion of a radially outer wall of the groove towards the inner wall of the groove.

Another object of the invention is to provide a novel and improved water-tight article that is made from a plastic container body having a bottom opening therein and a metal bottom plate where the plastic container body and the metal base plate have mechanically interlocked walls provided thereon for securing such members together by a permanent water-tight connection.

A further object of the invention is to provide a relatively uncomplicated, but positive method for securing the walls of a groove in a metal bottom plate to a protruding end wall of a plastic article for locking engagement between such walls, and yet another object is to use the resiliency in metal plate walls to seal them to a plastic wall received between a pair of metal walls.

The foregoing and other objects and advantages of the invention will be made more apparent as the specification proceeds.

Attention now is particularly directed to the accompanying drawings which show one currently preferred embodiment of the principles of the method of the present invention, and where:

30 FIG. 1 shows an elevation, partly in vertical section, of a container and a metal bottom plate therefor showing the parts in exploded, or unassembled relationship;

FIG. 2 is a fragmentary enlarged vertical elevation showing the first step in the engagement of a downwardly extending end wall of the plastic container with the upwardly facing or open groove in the bottom plate;

FIG. 3 is a fragmentary vertical section, like FIG. 2, showing the relation of the parts after the first shaping operation;

40 FIG. 4 is a fragmentary vertical section, like FIG. 2, but showing the shaping operation on the outer wall of the groove in the bottom plate;

FIG. 5 is a fragmentary vertical section, like FIG. 2, of the connection formed between the container and the bottom plate, after engagement is formed therebetween;

45 FIG. 6 shows a fragmentary vertical section of a modified article produced by the method of the invention but where a different type of a connection is provided between the bottom member and the container section, or body;

FIG. 7 is a fragmentary vertical section of a further type of container assembly of the invention; and

FIG. 8 is another fragmentary vertical section of a container provided by the invention.

55 The present invention, generally speaking, relates to a method of securing a plastic container to a metal bottom plate or member therefor which container and bottom member are secured together by, in one embodiment of the invention, an interlocked mechanical joint provided

60 between a downwardly extending end wall on the container received in a downwardly extending but upwardly open groove in the bottom plate formed by vertically extending groove walls, and where the method comprises, in one embodiment, the steps of forcing the inner wall of the groove radially outwardly primarily at the upper end thereof to incline such inner wall outwardly, and rolling the outer wall of the groove radially inwardly primarily at the upper margin thereof to incline such wall to extend

65 inwardly of the groove while supporting the inner wall primarily adjacent the lower end thereof to provide a

mechanical interlock between the end wall and the groove walls of the base plate.

Attention now is particularly directed to the details of this structure shown in the drawings and the method steps of the invention shown in the drawings. In the method of the invention, some type of a plastic container or body, indicated as a whole by the numeral 1, is adapted to be secured to a metal bottom plate 2 therefor to form an Article A. Normally this plastic container 1 can be made from any high temperature or heat resistant plastic, such as polypropylene, which plastic can be compounded in a conventional manner so that it will only have a melting or fusing temperature of about 330° F. Such container 1 has a downwardly extending end wall 3 formed thereon, which wall may be formed in the bottom of the container 1 and with the end wall 3, for example, being annular, and usually extending vertically. Such end wall 3 is adapted to be received in an upwardly open groove 4 provided in the metal bottom plate 2 by a radially inner wall 5 and a radially outer wall 6 with such groove walls usually being parallel and complementary in size and shape to the container wall 3 to receive it snugly therein. The metal bottom plate 2 may be adapted to position suitable means, such as any conventional or other electric heater member (not shown) thereon with the container 1, or such metal bottom plate may just be a plate for forming a liquid containing compartment with the container 1, as desired.

In order to secure the bottom plate 2 to the container 1, initially the inner wall 5 has a forming tool, such as a roll 7, brought into engagement therewith. Such roll 7 has a contour and is so positioned with relation to the vertical that the positioning axis, or shaft 8, for example, of the roll 7 is inclined at a slight acute angle, such as 5°, to the horizontal when the surfaces of the roll 7 are substantially cylindrical for good rolling action. The edges of the roll are radiused to avoid any sharp rolling edge engaging the walls of the groove or channel 4. In all events, the surfaces of the roll 7 are so formed as to engage the inner wall 5 primarily at the upper end thereof and, by a progressive movement of the roll 7, for example, the inner wall 5 is ultimately shaped to substantially the position shown in FIG. 3, or so that the upper end is distorted radially outwardly. As shown, the inner wall extends at an acute angle, such as about 5°, radially outwardly and upwardly of the bottom plate to form a mechanical engagement with the end wall 3 at least at the upper portion thereof where it connects to the remainder of the container 1.

In order to obtain a further mechanical interlock with and a better bond of the groove 4 and its walls with the end wall 3, a second forming means, such as a suitably driven roll 9 is provided and is positioned on a suitable support shaft 10. It is an important feature of the invention that this roll 9 is so positioned, or shaped as to engage the upper portion of the outer wall 6 and to progressively roll or move at least such upper end of the outer wall axially inwardly of the bottom plate 2 by movement of the roll 9 relative to the outer wall 6. Preferably the support shaft 10 so positions the roll 9, or the roll is contoured so that such outer wall can be shaped to extend inwardly of the bottom plate at an angle of approximately 12°, for example, with relation to the vertical and form a reduced distance between the adjacent surfaces of the walls 5 and 6 of the groove 4 to provide a pinching action on the plastic end wall 3. Normally the plastic forming such wall is of a relatively hard, but yet plastic or yieldable composition whereby sufficient pressures applied thereto will cause some cold flow of the plastic to adjust itself to the space provided. The outer wall 6 usually is deflected to a greater degree or angle than the inner wall 5.

It is an important feature of the invention that the inner wall 5 is supported, or reenforced while the roll 9 is brought into engagement with the outer wall 6. This

reenforcement provided for the inner wall 5 may be in the form of a support member, indicated at 11 in FIG. 4, and which support has a flat front edge surface 11a that engages primarily with the inner wall 5 only adjacent the lower end thereof. By this particular type of rolling or shaping action provided by the invention, the upper portion of the inner wall 5, indicated at 5a, due to its contour and prior working, will have a resilient resistance set up therein to axial inward movement thereof by the pressures applied to the outer wall 6 by the roll 9. Possibly this section 5a of the inner wall may be forced radially inwardly, or be reshaped to a vertical position by the action of the roll 9. So as to avoid any vertical deformation of the center portion of the bottom plate 2, a support member 12 is associated with the upper face of the bottom plate to prevent distortion thereof during the rolling action by the roll 9. The bottom plate may also be reenforced during the operative action of the roll 7, if desired.

FIG. 5 shows the upper portions 5a and 6a of the walls 5 and 6, respectively, will provide a good mechanical interlock between the walls of the groove 4 and the end wall 3 of the plastic container whereby even though axially directed separating forces are applied to the connection between the bottom plate and the container wall, still an effective, tight, bonded interlock will be obtained and maintained therebetween to provide a permanent water-tight, or liquid-tight connection therebetween. Such connection is aided, usually, by some cold flow of the plastic material forming the container wall. The actual connection of the groove 4 and end wall 3 may be in a vertical direction, or be slightly inclined with relation to such direction.

FIG. 6 of the drawing is of interest because a modified metal bottom plate or member 2a is secured to a container 1a. In this instance, the metal bottom plate has an upwardly extending section 20 formed therein with an upwardly open groove 4a formed therein by means of an outer wall 21 and an inner wall 22. In this instance, the inner wall 22 has two thicknesses of the bottom plate provided therein, as indicated at 23 and 24, and with the adjacent walls of these portions 23 and 24 of the inner wall being directly abutted against each other by being bent into tight contact with each other in their original forming operation. Preferably this inner wall 22 is radially offset from the radially outer wall 21, which wall 21 lies in the normal contour of the upwardly extending section 20 of the bottom plate 2a.

The rolling or shaping actions provided for this container 1a and bottom plate or member 2a would be exactly the same in principle as those outlined hereinbefore. Any suitable reenforcing, rolling, or forming members can be introduced through the open tops of the containers 1 and 1a, or through any openings that may be provided in the metal bottom plates 2, or metal bottom members 2a of the assemblies to be associated within the forming or shaping tools applied to the outside of the plates.

Usually the metal bottom plates 2 and 2a are made from uniform thickness sheets of some material that is a poor heat conductor, such as stainless steel, but it is within the scope of the invention to form these members from other conventional materials, such as aluminum. The containers made by the invention are particularly desirable when the bottoms therein are formed from stainless steel as this prevents transmission of high temperatures from the electric heater means secured to the centers of the bottom plate 2, when used in percolators, out to the radially outer margins of the bottom plates or members so that the plastic in the container assembly is not severely heat stressed by normal use thereof.

It will be realized that the rolls 7 and 9 shown in the drawings are indicated as having a smaller effective rolling width than the height of the flanges or walls 5 and 6 on which the rolling action of the invention is effected.

Hence, there will be some relatively vertical movement of the roll along these walls for the desired compressing action on the plastic container wall. However, in some instances, it may be desirable to provide just a localized rolling action to provide more or less of a bead or rib on the inner wall 5, for example, or on the outer wall 6 and still a very desirable securing action will be obtained by localized pressure action on the container wall 3.

In the modification of the invention shown in FIG. 7, a metal base plate 2b is provided that has an initially outwardly inclined groove 4b formed therein. Such groove 4b would have one wall 6b thereof of a shape as indicated in dotted lines in FIG. 7 and, after engaging the container, the wall 6b would be suitably worked or forced over into engagement with a horizontally extending flange 30 on a container 2b adjacent an opening in the bottom thereof. This shaping of the wall 6b can be done by a roll, like the roll 7, brought into engagement with the wall 6b. A wall 5b forming the inner wall of the U-shaped groove 4b provided on the metal base plate 2b is preferably initially shaped to extend upwardly at an angle to the horizontal of about 5°. Such rib or groove 4b, when permanently positioned, is horizontally extending and is facing radially inwardly of the container assembly to engage the flange or wall 30. The wall 5b hence provides a resilient resistance to deformation when the wall 6b is brought into final engagement with the container wall 30. It will be realized that the wall 5b can be suitably reinforced when the localized rolling action is performed on the other wall of the groove.

In the embodiment of the invention shown in FIG. 8, a bottom plate 2c has, in effect, a radially outwardly facing horizontally directed groove 4c formed integrally therewith. Suitably positioned means can be inserted, as for example through an aperture provided in the center portion of the bottom plate 2c and from the top of a container 1c, to provide a desired rolling and support action on the opposed walls of this groove 4c, as one or both of such groove walls are forced into engagement with a horizontally extending wall, or flange 41 formed on the container 1c adjacent a bottom opening therein. Initially an upper wall 6c of the groove 4c would be upwardly directed and be forced over to the position shown after the container and the bottom plate are associated for permanent assembly thereof. A wall 5c of the groove may abut on an adjacent portion of the bottom plate and be worked to an inclination to the horizontal of about 5° before the bottom plate and container are assembled.

While it is not the preferred practice of the invention, in some instances it is possible to obtain satisfactory sealed connection between the container wall 3 and the bottom plate of the invention by either a rolling action, preferably localized, performed solely on the inner wall 5 or on the outer wall 6, as desired, but the preferred practice of the invention utilizes a rolling action on both of such walls, as described hereinbefore in more detail.

The term "plastic" in the present application is used in its normal commercial sense to refer to a material which has some cold flow under pressure, which has some flexibility, and which is not brittle like glass. Plastic generally refers to synthetic or semi-synthetic organic substances made by polymerization or condensation, or are derived from a natural material by chemical action and which can be molded, cast, extruded, drawn, or laminated under various conditions. The plastic material may either be a thermosetting or a thermoplastic substance within the limits outlined hereinabove, and can be readily made of attractive color and design. Or, combinations of thermosetting and thermoplastic materials by lamination or otherwise that permits substantial but resilient pressures to be transmitted thereby can be used in making the container 1 or the like.

When desired, a suitable adhesive could be used to aid in bonding the metal plates to the plastic containers. Such adhesive action may include heating the metal plate, 75

when a heat softening plastic is used, at some stage in the attaching process.

It can be said that the invention relates to the deforming of at least a portion of a first wall of a groove in a metal plate in one direction and then deforming the other wall of the groove in the opposite direction but towards the first wall. Force is transmitted through the slightly resilient plastic material forming the wall positioned in the groove. The first metal wall has a spring resistance to the deformation thereof by the force applied to the other wall to aid in obtaining a good permanent liquid tight bond in the container.

Obviously, the size and shapes of the actual rolls of forming members 7 and 9 used in the apparatus of the invention may be varied, but with the shaping actions obtained being those described herein. Such shaping actions on the walls 5 and 6 may provide a rib or ribs thereon protruding towards the opposite wall by a localized rolling action. A localized rib x is shown in FIG. 8. Only the walls 6b and 6c would need to be rolled after assembly of the containers and bottom plates in FIGS. 7 and 8.

Any suitable base, or support means may be attached to the containers of the invention in known manners. Suitable electric controls also can be provided and be connected to the electric heaters, when used, to complete the small, electric appliances.

By the invention, pairs of continuous, spaced walls of a metal disc or member are brought into engagement with a plastic container adjacent an opening therein, which walls may extend either substantially vertically, or horizontally. Thus it is believed that the objects of the invention have been achieved.

While several complete embodiments of the invention have been disclosed herein, it will be appreciated that modification of these particular embodiments of the invention may be resorted to without departing from the scope of the invention as defined in the appended claims.

What is claimed is:

- 40 1. A method of securing a plastic container and a metal bottom plate therefor together to provide a watertight article, which method comprises the steps of forming a container having an annular downwardly extending end wall defining an opening in the container bottom, providing a metal base plate for the container, which base plate has an annular downwardly extending upwardly open groove therein for receipt of said end wall, inserting said end wall into said groove, rolling the inner wall of said groove radially outwardly by pressure applied only adjacent the upper end thereof to incline such wall upwardly and outwardly, and rolling the outer wall of said groove radially inwardly at the upper margin thereof by pressure applied only adjacent the upper end of such outer wall to incline such wall to extend downwardly and outwardly at a greater angle to the vertical than the inner wall while supporting said inner wall against radially inwardly movement only adjacent the lower end thereof, to form a mechanical interlock between said end wall and said base plate.
- 45 2. A method of securing a plastic container and a metal bottom plate therefor together to provide a watertight article, which method comprises the steps of forming a container having an annular downwardly extending end wall defining an opening in the container bottom, providing a metal base plate for the container, which base plate has an annular downwardly extending upwardly open groove therein for receipt of said end wall, forcing said end wall down into said groove,
- 50
- 55
- 60
- 65
- 70
- 75

forcing the inner wall of said groove radially outwardly at only an upper end section thereof to move such wall section outwardly, and
forcing the outer wall of said groove radially inwardly only at the upper end section thereof to move such wall section to extend inwardly to form a mechanical interlock between said end wall and the walls of said groove in said base plate.

3. A method of securing a plastic container and a metal bottom plate therefor together by an interlocked joint between a downwardly extending end wall in the container positioned in a downwardly extending upwardly open groove in the bottom plate formed by vertically extending radially inner and outer groove walls to provide a water-tight article, which method comprises the steps of
forcing the inner wall of said groove radially outwardly primarily at the upper end thereof to incline such inner wall upwardly and outwardly,

rolling the outer wall of said groove radially inwardly primarily at the upper margin thereof to incline such wall to extend downwardly and outwardly of the groove while supporting said inner wall primarily adjacent the lower end thereof, to form a mechanical interlock between said end wall and said bottom plate, and

reinforcing the upper surface of said bottom plate adjacent said groove while rolling said outer wall.

4. A method of securing a plastic container and a metal bottom section therefor together by an interlocked joint between a downwardly extending end wall in the container received in an upwardly open groove in the bottom section formed by vertically extending, radially spaced inner and outer groove wall means to provide a water-tight article, which method comprises the steps of
forcing the inner wall means of said groove radially outwardly only adjacent the upper end thereof to indent such inner wall means outwardly,

forcing the outer wall means of said groove radially inwardly only adjacent the upper margin thereof and opposed to the indent in the inner wall to dent the outer wall means inwardly of the groove to form a mechanical interlock between said end wall and said bottom section, and

reinforcing the upper surface of said bottom section adjacent said groove while forcing said outer wall means inwardly.

5. A method of securing a plastic container and a metal bottom section therefor together by an interlocked joint between a downwardly extending end wall in the container received in an upwardly open groove in the bottom section formed by vertically extending, radially spaced inner and outer groove wall means to provide a water-tight article, which method comprises the steps of
forcing the inner wall means of said groove radially outwardly only at the upper end thereof to indent such inner wall means outwardly, and

forcing the outer wall means of said groove radially inwardly only at the upper margin thereof to indent such wall means inwardly of the groove to form a mechanical interlock between said end wall and said bottom section.

6. A method of securing a plastic container and a metal bottom therefor together by an interlocked joint between a downwardly extending end wall in the container outlining an opening therein and an upwardly open groove in the bottom formed by vertically extending radially spaced groove walls to provide a water-tight article, which method comprises the steps of
inserting the end wall into said groove,

10
15

rolling the inner wall of said groove radially outwardly above the lower end thereof, and
rolling the outer wall of said groove radially inwardly above the lower margin thereof to force such wall against said container end wall to form a mechanical interlock between said container end wall and said groove walls.

7. A method of securing a plastic container and a metal bottom section therefor together by an interlocked joint between a downwardly extending end wall in the container received in an upwardly open groove in the bottom section formed by vertically extending, radially spaced inner and outer groove wall means to provide a water tight article, which method comprises the steps of
forcing the inner wall means of said groove radially outwardly at the upper end thereof to deflect such wall means at an angle of about 5° to the vertical, and

forcing the inner wall means of said groove radially inwardly to incline part of such wall means inwardly of the groove at a greater angle to the vertical than said inner wall means, said inner wall means resiliently resisting distortion from forces on said outer wall means.

8. A method of securing a plastic container and a metal bottom plate therefor together by an interlocked joint between a protruding wall in the container adjacent an opening therein and a generally U-shaped peripheral groove in the bottom plate formed by a pair of substantially parallel spaced groove walls to provide a liquid-tight article, which method comprises the steps of
bringing the container wall and said groove into engagement with such container wall between said groove walls,

rolling one wall of said groove towards the other wall primarily adjacent the connection of such wall to the plate, and

rolling the other wall of said groove towards the first groove wall primarily at its upper end to compress said container wall between said groove walls.

9. A method of securing a plastic container and a metal bottom plate therefor together by an interlocked joint between a protruding end wall in the container adjacent an opening therein and an open generally U-shaped in section peripheral integral groove in the bottom plate formed by spaced inner and outer groove walls to provide a liquid-tight article, and where the plastic forming said container will cold flow under pressure, which method comprises the steps of
bringing the end wall and the groove walls into engagement, and

forcing one wall of said groove towards the other groove wall by a force applied only to an upper portion of such groove wall to compress the container wall therebetween to cause cold flow of the plastic material forming such wall, and form a mechanical interlock between said container end wall and said groove walls.
